US00D864236S

(12) **United States Design Patent** (10) Patent No.: **US D864,236 S**
Henderson et al. (45) Date of Patent: **** Oct. 22, 2019**

(54) **DISPLAY SCREEN OR PORTION THEREOF
WITH ANIMATED GRAPHICAL USER
INTERFACE**

- (71) Applicant: **Apple Inc.**, Cupertino, CA (US)
(72) Inventors: **Ian M. Henderson**, Portola Valley, CA (US); **Chanaka Karunamuni**, Cupertino, CA (US); **Martin Pedrick**, San Francisco, CA (US)
(73) Assignee: **Apple Inc.**, Cupertino, CA (US)
(**) Term: **15 Years**
(21) Appl. No.: **29/659,111**
(22) Filed: **Aug. 6, 2018**

CLAIM

The ornamental design for a display screen or portion thereof with animated graphical user interface, as shown and described.

DESCRIPTION

FIG. 1 is a front view of a display screen or portion thereof with animated graphical user interface showing a first image of the claimed design;

FIG. 2 is a second image thereof;

FIG. 3 is a third image thereof;

FIG. 4 is a fourth image thereof; and,

FIG. 5 is a fifth image thereof.

The outermost broken lines in the figures show a display screen or portion thereof, and form no part of the claimed design. The other broken lines in the figures show portions of the animated graphical user interface that form no part of the claimed design.

The appearance of the animated image sequentially transitions between the images shown in FIGS. 1-5. The process or period in which one image transitions to another forms no part of the claimed design.
